URINAL SCREEN

Lester S. Miller, Clayton, Mo., assignor to Paeco Rubber Company, Inc., Ravenna, Ohio, a corporation of Ohio

Application October 11, 1955, Serial No. 38,323

Term of patent 14 years

(Cl. D4—5)

I claim:

The ornamental design for a urinal screen, substantially as shown.
